SKIRT DISPLAY DEVICE

George A. Scherquist, Los Angeles, Calif.

Application May 13, 1946, Serial No. 669,415

3 Claims. (Cl. 223—95)

This invention relates to a garment hanger and particularly pertains to a skirt display device.

In retail clothing establishments where ladies' ready-to-wear garments, such as skirts, are displayed and sold, it is desirable to maintain a selection of skirts in stock and to hang them so that they will not become mussed, may be displayed easily, and also may be easily placed upon a display hanger or removed therefrom. It is the principal object of the present invention, therefore, to provide a skirt display hanger which may form one of a set of hangers adapted to be mounted upon a wall or other vertical supporting member, and which hangers individually receive a skirt and hold it in a manner to prevent it from becoming creased and permit it to be inspected from any angle.

The present invention contemplates the provision of a vertical supporting member upon which pivot brackets may be secured, each of said brackets providing a vertical pivot for a horizontal swinging supporting arm, said supporting arms each being fitted with a pair of fingers yieldably held to be encircled by a skirt band and to engage the same in a manner to support a skirt.

The invention is illustrated by way of example in the accompanying drawing in which:

Figure 1 is a view in perspective showing the application of the present invention and indicating a skirt in dotted lines as supported by one of the hangers.

Fig. 2 is an enlarged view in vertical section and elevation showing the preferred form of the present invention and the details of its construction, the view having parts broken away for the sake of convenience.

Fig. 3 is a view in vertical section and elevation showing another form of the invention with parts broken away for the sake of convenience.

Referring more particularly to the drawing, 10 indicates a supporting structure. This may be of any desired type so long as a vertical supporting member is provided to receive brackets 11. The brackets 11 as here shown are of channel section having a web 12 which extends vertically and is secured to the support 10 by screws 13. The horizontal legs 14 and 15 of the bracket are spaced from each other and are formed with aligned openings 16 through which a vertical pivot pin 17 extends. In the form of the invention shown in Fig. 2 of the drawing the vertical pivot pin carries an enlarged head structure 18 at its upper end, thus providing a shoulder 19 which rests upon the upper face of the leg 14. The head 18 is formed with a horizontal bore 20 into

which a tubular supporting arm 21 is fitted. This arm extends horizontally and is here shown as being secured in position by a pin 22 which extends transversely through the arm 21 and the head 18. It will be seen that the arm 21 is thus free to swing horizontally upon the axis of the pivot pin 17. Mounted upon the outer free end of the arm 21 is a skirt supporting element 23 which comprises a head 26 formed integrally with a downwardly projecting finger 25. Formed in the head 26 is a bore 24 which receives the outer free end of the tubular arm 21 and is connected therewith by a fastening pin 27. Attention is directed to the fact that the longitudinal axis of the bore 24 is at an angle to the longitudinal center of the finger 25 so that the finger 25 extends downwardly and outwardly. Mounted within the tubular arm 21 is a guide rod 28 which slides longitudinally of the tubular member 21. Interposed between the outer end of the guide rod 28 and the fastening pin 27 is a spring 29. This spring tends to force the guide rod 28 in the direction of the arrow a, as indicated in Fig. 2. Extending longitudinally of the lower face of the tubular supporting arm 21 is a longitudinal slot 30 which is formed through the wall of the tubular member 21. The slot 30 is provided to accommodate the upper end of a skirt supporting member 31. This member has a finger portion 32 similar to the finger portion 25 of the skirt supporting member 23. This finger extends downwardly and at an angle opposite to that of the member 25. Thus, the fingers 25 and 32 flare oppositely and outwardly so that when they are encircled by the waist-band and upper portion of a skirt they will tend to hold the skirt in place thereon. The upper end of the skirt supporting member 31 has a flat extension 33 of reduced width. This extension projects through the longitudinal slot 30 in the arm 21 and also into a transverse slot formed in the end of the rod 28. Thus the skirt supporting member 31 is fixed to move with the rod 28. Disposed within the tubular supporting member 21 and resting against the fastening pin 22 is a stop rod 34. The end of the rod 28 abuts against this stop rod and limits the movement of the skirt supporting member 31 with relation to the bracket 11. This insures that the supporting arm 21 may have a desired arcuate movement around the axis of the pivot pin 17 so that a skirt supported thereby may be viewed and inspected from any angle.

In the form of the invention shown in Fig. 3 of the drawing a modified construction is provided although the principle is substantially the same as

previously described. The fundamental difference is that the skirt supporting members in the structure shown in Fig. 3 are moved apart by spring tension whereas in the structure of Fig. 2 this movement was produced by spring expansion. In Fig. 3 of the drawing a horizontal supporting arm 35 is provided. This arm is tubular and fits upon a horizontal leg 36 of a pivot member 37. A vertical leg 38 of the pivot member 37 extends through the opening 16 in the supporting bracket 11. Fixed upon the outer end of the supporting arm 35 is a sleeve 39 which carries a downwardly extending skirt supporting finger 40. The outer face of this finger is inclined as previously described for finger 25. The tubular supporting arm 35 is formed with a longitudinal slot 41 in its lower face. This slot accommodates a skirt supporting member 42 which extends through the slot and is carried by a tubular rod 43. The tubular rod 43 slides within the supporting member 35 and receives a tension spring 44 which is secured at one end to a pin 45 and at its opposite end to a pin 46. The pin 45 is fixed to the supporting member 35 and the pin 46 is fixed to the outer end of the tubular rod 43. Thus, when the skirt supporting member 42 is moved toward the skirt supporting member 40 the spring 44 will be placed under tension.

In operation of the present invention one or more of the skirt supporting and display units may be mounted upon the support 16. If a plurality of the units is required they are spaced a required distance from each other so that they may be easily swung to disclose the skirts from all angles. When a skirt is to be applied to one of the hangers the skirt supporting members 31 or 42 are moved toward the supporting members 23 or 40 until the finger portions of these members may be inserted within the waist-band of the skirt, after which the supporting members 31 or 42 are released so that the springs 29 or 44 will act to spread the complementary skirt supporting elements until they have drawn the skirt band taut. It is to be understood that the skirt band has previously been fastened so that when it is drawn taut by the supporting elements the skirt will be held on the oppositely inclined fingers of the supporting elements. This insures that the skirt will be supported so that it will not be wrinkled, and so that it may be displayed to the best advantage when inspected by a customer.

It is to be understood that while the outer skirt supporting member is here shown as being fixed that the invention is not limited to this construction but involves the use of a pair of supporting members tending to have relative movement with each other.

It will thus be seen that the structure here disclosed is simple in construction and operation, that it provides means whereby a skirt may be easily engaged to be supported and displayed, and may be removed conveniently from the support when desired.

While I have shown the preferred form of my invention as now known to me, it will be understood that various changes may be made in combination, construction and arrangement of parts by those skilled in the art, without departing from the spirit of my invention as claimed.

Having thus described my invention, what I claim and desire to secure by Letters Patent is:

1. A skirt display and supporting device com-

prising a mounting bracket adapted to be positioned upon a vertical support, a pivot pin carried by said bracket for rotation around its vertical axis, a rigid tubular arm carried by the pivot pin to swing in a horizontal plane and having a longitudinal slot in its lower side, a fixed skirt supporting member mounted at the free end of said arm, a movable skirt supporting element extending downwardly through said slot and being complementary to the fixed skirt supporting element, a slidably guide rod within said arm and to which said movable skirt supporting element is secured, and a spring enclosed within said tubular arm and acting to urge the movable skirt supporting element away from the fixed skirt supporting element.

2. A skirt display and supporting device comprising a mounting bracket adapted to be positioned upon a vertical support, a pivot pin carried by said bracket for rotation around its vertical axis, a rigid tubular arm carried by the pivot pin to swing in a horizontal plane and having a longitudinal slot in its lower side, a fixed skirt supporting member mounted at the free end of said arm, a movable skirt supporting element extending downwardly through said slot and being complementary to the fixed skirt supporting element, a slidably guide rod within said arm and to which said movable skirt supporting element is secured, and a spring enclosed within said tubular arm and acting to urge the movable skirt supporting element away from the fixed skirt supporting element, said skirt supporting members extending downwardly and oppositely from each other at equal angles to the vertical.

3. A skirt display and supporting device comprising a mounting bracket having upper and lower aligned bearing portions, a pivot pin extending vertically through said bearing portions and being rotatable, said pin having an enlarged head at its upper end providing a supporting shoulder resting upon the upper one of said bearing portions, a tubular arm rigidly connected at one end to said head portion and adapted to swing horizontally around the vertical axis of said pin, a downwardly extending skirt supporting member fixed on the free end of said tubular member, a longitudinally extending slotted passageway formed in the lower side of said tubular member, a movable skirt supporting member extending downwardly through said passageway, a longitudinally extending cylindrical guide rod disposed within said tubular member and to which said last named supporting member is attached, said guide rod being free to move longitudinally, and a spring disposed within said tubular member and tending to urge the movable skirt supporting member away from the fixed supporting member.
